UNITED STATES PATENT OFFICE.

ARVAL BARR, OF NEWBURG, INDIANA.

EMERGENCY-LOCK.

1,232,182.

Specification of Letters Patent.

Patented July 3, 1917.

Application filed February 7, 1917. Serial No. 147,180.

To all whom it may concern:

Be it known that I, ARVAL BARR, a citizen of the United States, residing at Newburg, in the county of Warrick, State of Indiana, have invented certain new and useful Improvements in Emergency-Locks; and I do hereby declare the following to be a full, clear, and exact description of the invention, such as will enable others skilled in the art to which it appertains to make and use the same.

This invention relates to emergency locks for use in banks, cashiers' offices, and like places.

15 The object of the invention is to provide an emergency lock which may be set in operation simultaneously with the sending of alarms to a police station or other headquarters, the lock being electrically actuated to be effective during the time that a suitable electric circuit is closed, the latter having been energized by a foot operative switch or similar emergency switch within reach of the cashier or other guardian.

20 25 A further object of the invention is to construct a form of electric lock for doors which will serve as an emergency device for locking the doors of a banking room or cashier's cage until help can arrive, the lock 30 consisting of a rotary element which could not readily be tampered with, since it is wholly inclosed within the door body and comprises chiefly a rotary element which rotates across the joint between the door 35 and the adjacent casing or companion door at a high rate of speed so that, until it is again brought to rest, it effectively prevents the breaking of the joint.

40 45 A still further object of the invention is to provide such a rotary locking element which, in itself constitutes an electric motor structure so that it may be readily embedded in the body of a door or within a door frame.

50 45 With the above objects in view, and such others as may hereinafter appear, my invention will now be fully set forth and described, reference being had to the accompanying drawings:—

55 In the drawings:—

Figure 1 is an elevation of a part of a door and door casing broken away to show the installation of my invention,

Fig. 2 is an enlarged view of the locking 55 element,

Fig. 3 is a section on line 3—3 of Fig. 1, and

Fig. 4 is an elevational view of a foot actuated switch together with a diagrammatic showing of the wiring of the lock. 60

Referring more particularly to the drawings, 1 represents a semi-circular casing having the cover plate 2. The straight side of the casing 1 is adapted to stand flush with the free edge of a door 3 when the casing 65 is embedded therein, and is provided with a vertical slot 4 through which the locking element 5 may operate. The element 5 is, in general shape, a fan-like structure formed of the radiating arms 6 which all lie upon one side of a diametrical or base arm 7. One end of the base arm 7 is weighted, so that when the element 5 is journaled within the casing 1, all of the arms 6 will extend inside of the casing, and the arm 7 will 70 lie substantially parallel with the straight side of the casing, without projecting therethrough. The element 5 is journaled upon a spindle 8 extending transversely through the casing at a suitably intermediate point, and acts as the point of rotation of the element 5. A motor structure 9 is mounted upon the spindle 8 within a housing 10 secured to the inner face of the door, the motor being connected in the alarm circuit 75 as will later appear, to be energized simultaneously with the sounding of the alarm. 80

The switch 15 consists of a base block 16 which is pivotally mounted to preferably 90 extend below the floor. Upon the block 16 is mounted the foot piece 17, the latter standing vertically and at the opposite end to the depending contact element 18 which projects below the floor level. Contact elements 18 and 19 carried respectively by the element 16 and the angle bracket 20 are adapted to interengage when the foot piece 17 is actuated to close the circuit through the alarm mechanism 21 and the lock motor. 95 100

As soon as the circuit is closed, so that the motor 9 is energized, its rapid revolution also rotates the locking element 5, so that the arms 6 and 7 are thrown outwardly through the slot 4 and into the recess 22 105 formed in the door casing or companion door, the speed with which the element 5 rotates causing the latter to practically form a continuous disk across the joint between the door and the door casing which it is 110

practically impossible to tamper with and whose presence is not evident since it does not appear upon the exterior of the door. As soon as the circuit is broken again, the 5 motor is deenergized so that the locking element 5 may come to rest, by reason of the weighted arm 7, the arms 6 are caused to come to rest within the casing 1, so that the door may be opened without interference 10 from the lock.

From the foregoing it will be evident that I have provided a very complete and effective emergency lock for door closures, and that the nature of the lock is such that it 15 cannot be readily tampered with within the period of time which is left to burglars or others attempting to break into the inclosure after the alarm signals have been sent in.

What I claim as my invention is:—

20 1. An emergency lock comprising in combination with a door and its companion element having registering recesses, of a freely rotatable element counterweighted to lie wholly within one of the recesses when at 25 rest, and mounted therein to be rotated through both of the recesses, and means to continuously and rapidly rotate said element.

2. An emergency lock comprising in combination with a door and its companion ele-

ment having registering recesses, of a freely rotatable element mounted in one of said recesses and consisting of a plurality of arms radiating from the center of rotation and lying wholly to one side thereof, said element being weighted to cause it to lie wholly within its recess when at rest, and means for continuously and rapidly rotating said element through both of the recesses to lock the door. 35

3. An emergency lock comprising in combination with a door and its companion element having registering recesses, of a rotary element mounted in one of said recesses and consisting of a plurality of arms radiating from the center of rotation and lying wholly to one side thereof, said element being weighted to cause it to lie within its recess when at rest, a motor mounted on the axis of said element for rotating the latter when energized, whereby to lock the door by the rapid projection of the element into the opposite recess. 45

In testimony whereof, I affix my signature, in the presence of two witnesses.

ARVAL BARR.
